HYDRAULIC CONTROL VALVE

Hans C. Weimar, Providence, R. I., assignor to
 Brown and Sharpe Manufacturing Company,
 Providence, R. I., a corporation of Rhode Island

Application May 25, 1948, Serial No. 29,042

8 Claims. (Cl. 251—34)

1

The present invention relates to an improved hydraulic control valve, and is herein disclosed in a preferred form as embodied in a speed control valve adapted for controlling the rate of movement of a machine tool support as, for example, a hydraulically actuated grinding machine work supporting table.

It is a principal object of the invention to provide a novel and improved control valve of which the movable valve element is adapted for adjustment by substantially evenly spaced increments of movement over a reasonable range from a closed to a fully opened position, and of which the throttle opening is arranged to be adjusted by said increments of movement from a closed to a fully opened position to provide a series of accurately determined very slow speeds of the driven support which may range, for example, from one to several inches per minute, and thereafter a series of more widely spaced higher speeds as the valve element approaches its fully opened position.

It is a further object of the invention to provide a novel and improved control valve of which the throttle opening is increased proportionately as the square of the distance moved by the movable valve element, which is simple and economical in construction, and adapted for easy manual adjustment for the accurate control of the rate of support movement.

It is a further object of the invention to provide a simple and efficient valve construction including means available in initially adjusting the valve mechanism to accurately ascertain the starting position of the valve and to provide accurate calibration of the valve particularly over the very slow speed range in accordance with a simple and effective method of adjustment hereinafter more fully set forth.

With the above and other objects in view as may hereinafter appear, a principal feature of the invention consists in the provision of cylindrical valve and sleeve elements which are in screw-threaded relation to one another so that a combined rotational and axial movement of one element relative to the other is effected, and which are formed with rectilinear apertures arranged to be moved diagonally into overlying relation. The arrangement is such that the relative movement of the valve parts is effective to increase the area of valve opening from the closed position in proportion to the square of the extent of said relative movement.

In the preferred embodiment of the invention illustrated, the rectangular aperture referred to

5 in the sleeve element is formed by means of a transverse cut of a depth extending nearly to the axis of the sleeve and of a width preferably greater than required for full valve opening. The 10 cooperating rectangular opening in the valve member is formed by slabbing off half the diameter of the valve member at its inner end. The effective opening or aperture of the valve in any 15 position is determined by the amount of overlap of the semi-cylindrical edge of the slabbed-off portion of the valve member and a transverse edge of the slot in the sleeve member in one direction and the amount of overlap of two cooperating side edges of the respective valve and sleeve 20 elements in the other direction.

Another feature of the invention consists in the novel construction and arrangement of the valve assembly to facilitate an initial accurate 25 adjustment of the valve mechanism including a rotatably adjustable nut into which the valve stem is threaded for imparting the desired rotational and axial movements to the valve member to open and close the valve. In the illustrated construction, the nut element is circular in form, and is angularly adjustable by means of a suitable pin wrench, being normally secured in adjusted position by means of an overlying clamping ring.

The several features of the invention consist 30 also in the devices, combinations and arrangement of parts and in the method hereinafter described and claimed, which together with the advantages to be obtained thereby will be readily understood by one skilled in the art from the 35 following description taken in connection with the accompanying drawings, in which Fig. 1 is a sectional view in side elevation of applicant's improved control valve illustrating particularly the arrangement of the valve and sleeve elements of the valve, the adjustable screw-threaded connection for effecting a combined rotational and axial movement of the valve element, and the manually operable control knob; Fig. 2 is an end view of the control knob and its associated dial shown in Fig. 1 looking from the left; Fig. 3 is a view similar to Fig. 2, but with the control 40 knob removed and portions of the underlying adjustable nut and associated clamp ring broken away and sectioned; Fig. 4 is a sectional view 45 taken on the line 4—4 of Fig. 1, showing the valve in its fully open position; Fig. 5 is a view similar to Fig. 4 showing the valve throttle and more particularly the side ports in intermediate or half-way position between fully opened and 50 shut-off position; Fig. 6 is a view similar to

Figs. 4 and 5, but with the valve shown in its fully closed position; Fig. 7 is a fragmentary developed view showing the relation of the valve stem and cylinder with the valve fully opened as shown in Fig. 4; Fig. 8 is a developed view similar to Fig. 5, in which the valve stem has been turned half-way to its shut-off position; Fig. 9 is a developed view of the parts in the shut-off position shown specifically in Fig. 6; Fig. 10 is a view of the valve control mechanism looking from the left, but with the manually operable knob removed and a pair of gauging devices applied respectively to the valve stem and rotatably adjustable nut preparatory for adjustment; Fig. 11 is a sectional view looking from the right taken on the line 11-11 of Fig. 10; Figs. 12 to 16 inclusive, are a series of developed diagrammatic views showing successive positions of the relatively movable valve elements in positions taken during the process of adjusting the device; Figs. 17 to 21 inclusive, correspond respectively with the positions of the valve elements shown in Figs. 12 to 16; and Fig. 22 is a diagram illustrating the manner in which the throttle opening of the valve and related rate of drive of the hydraulically driven support is increased in accordance with the parabolic law.

The control valve illustrated in the drawings as embodying in a preferred form the several features of the invention, is particularly adapted and is calibrated to control the rate of movement of a hydraulically-actuated grinding machine work supporting table having a range of operating speeds from one inch per minute up to any desired maximum, which may for example be the 144 inches per minute indicated on the dial of Fig. 2. In actual operation, a close control of the rate of travel of the table is desirable at the lower speeds, while at the same time provision must also be made for a reasonable range of operating table speeds at much higher feed rates. A difference of speed amounting to an inch per minute within the slow speed range extending from one to six inches of travel of the grinding machine table may be of considerable consequence, for example, in connection with wheel truing.

In carrying out the present invention, a simple and yet efficient valve mechanism has been developed, in which the movable valve element is arranged to be shifted through approximately equal increments of distance to successive positions of adjustment in order to provide for a substantial range of speeds in the slow speed range and a series of graduated speeds in the high speed range.

Referring specifically to the drawings, the improved control valve mechanism consists of a cylindrical valve member 12 which is supported within a sleeve member 14 fitted within a bore 60 in a casing 16 attached by bolts 18 to a portion 20 of the machine frame. Liquid under pressure is introduced into the valve assembly by means of an inlet duct 24, passes through a throttle opening in the valve, and is then discharged through an outlet 26 connecting with the outer end of the valve sleeve member 14. Cooperating ports are formed in the valve sleeve member 14 and valve member 12 which are rendered operative by a combined rotational and axial movement of the valve member 12 to control the amount of fluid passing through the valve.

A port 28 is formed in the valve sleeve 14 in the form of a transverse cut extending nearly to the axis of the sleeve 14, and of a width preferably

greater than is required for the maximum throttle opening of the valve. A cooperating port opening 30 is formed in the inner right hand end of the valve member 12 in the form of a semi-cylindrical cutout in the end of the valve member. With the valve in the fully opened position shown, for example, in Fig. 1, liquid under pressure is admitted through the inlet pipe 24 to the port 28, through the port 30 in the valve member, and thence outwardly to the right by way of the end of the valve sleeve 14 to the outlet pipe 26.

The valve member 12 is arranged to have imparted thereto a combined rotational and axial movement which has the effect of causing the rectangularly-shaped apertures provided by ports 28 and 30 to move diagonally into overlying relation at their adjacent corners to open so that the size of the aperture or throttle opening will increase in proportion to the square of the distance moved by the valve element 12. Specifically, the area of throttle opening increases in accordance with the formula for a parabola $x^2=ay$ where "x" is a unit of distance through which the valve element 12 is moved or turned, "y" is the area of throttle opening, and "a" is a constant factor determined by the dimensions of the valve and the units chosen for "x" and "y." For simplicity of illustration, the factor "a" is taken as unity in the graph Fig. 22.

The manner in which the valve opens is illustrated in graph form in Fig. 22. In this figure, the values of x and y have been arbitrarily chosen. In the graph, the x coordinate represents arbitrary units of the angle of valve opening. The y coordinate represents arbitrary units of area of valve aperture. The parabolic curve A is a curve of valve settings produced in accordance with the formula $x^2=ay$. The dot-and-dash diagonally extending line B is the graph of a valve such as the ordinary needle valve which opens in accordance with a straight line law, and is introduced solely for purposes of comparison. Fig. 22 demonstrates the advantage achieved by the improved valve disclosed which opens in accordance with the parabolic law. From the graph, it will readily be seen that the initial increments of movement of the valve from closed position to open, will effect a relatively small increase in aperture and consequent table speed, whereas, as the valve continues its movement to open, increments of movement of equal extent will produce much larger increases of aperture particularly adapted for adjustment of the valve in the high speed range.

For controlling the movement of the valve member 12, there is provided an enlarged valve stem 34 which passes through an oversize aperture 36 in the wall 20 of the machine frame, thence through an oversize aperture 38 in another wall portion 40 of the machine frame, and is formed with a screw thread 42 threaded through a nut 44 secured to the outer face of the wall 40. At its outer end the valve stem 34 has mounted thereon a manually operable control knob 46 which is secured in position on the stem by a set screw 48. As shown in the drawings, the nut 44 is formed with a circular outer edge having an annular flange 50 against which is fitted a nut clamping ring 52. A pair of clamping machine screws 54 passing through the clamping ring and screw-threaded into the wall 40 act to force the clamping ring 52 into clamping engagement with the nut 44 to hold the same in adjusted position. A group of four recesses 75 56 formed in the outer face of the nut 44 are

adapted to receive a suitable pin wrench for the adjustment of the angular position of the nut as hereinafter fully set forth. A stop pin 58 mounted to extend outwardly from the face of the clamping ring 52 projects into an annular groove 60 formed in the under face of the manual control knob 46 to positively limit angular movement of the control knob and valve stem 34 therewith in either direction.

In order to insure the accurate positioning of the valve member 12 axially of the valve sleeve 14 irrespective of any looseness or wear which may exist between the screw 42 and nut 44 elements, a helical take-up spring 64 is coiled about the valve stem 34 between a washer 66 retained on the valve stem 34, and a sleeve abutment 68 arranged to bear against the left hand or outer face of the wall 20 of the casing. With this construction it is appreciated that an axial jogging of the control knob 46 and valve stem 34 against the pressure of the spring 64 will have the effect of momentarily changing the speed of the driven support. It is appreciated further that such an accidental jogging which might tend to increase the feed rate would involve a serious hazard of overloading and damage both to the machine and to the work being operated upon. With the illustrated construction, the thrust of the spring upon the valve stem 34 and control knob 46 is outward to open for the adjusted position of the valve. The illustrated construction thus not only provides for the advantageous use of the take-up device in the screw and nut connection to insure a high degree of accuracy in adjustment, but is further arranged so that any accidental pressure brought against the control knob during operation, could only move the valve inwardly to close against the pressure of the spring 64, and thus could only cause a momentary and harmless slowing of the driven support. In order to avoid any possible tendency of the take-up spring 64 or its associated abutments 68 to become frictionally engaged against the wall 20, with the result that torsional strains may be set up in the spring 64 tending to move the valve stem 34 and associated parts rotationally from adjusted position, the sleeve abutment 68 is keyed to turn with and to slide with relation to the valve stem 34 by means of a key 70 passing through a slot in the valve stem.

As illustrated, for example, in Figs. 1 and 2 of the drawings, the control knob 46 is formed to provide an indicator dial 71 having calibrated markings thereon to cooperate with a relatively stationary marker 72 carried on the nut clamping ring 52. With the illustrated construction, the dial 71 is calibrated in terms of inches per minute of travel of a hydraulically-actuated grinding machine work supporting table. These calibrations include a group of very slow table speeds from 1 to 6 inches per minute, and a group of more rapidly increasing higher speeds ranging from 16 to 144 inches per minute.

The manner in which the ports 28 and 30 are moved with relation to one another to cause the throttle opening to be increased in proportion to the square of the increment of movement of the valve stem 34 will be readily understood from an inspection of Figs. 4 to 6 showing the valve respectively in its fully opened, partly opened and fully closed positions taken in connection with the diagrammatic developed views of the parts in the corresponding positions of Figs. 7, 8 and 9. Starting with the fully closed position of Fig. 6, it will be seen that the valve member 12 is turned

so that the projecting semi-cylindrical end portion of the valve member 12 designated at 74 is turned to fully blank off the sleeve port 28, while at the same time the valve member has been moved inwardly, or to the right from the position shown in Fig. 1, into its sleeve 14 to such an extent that the transverse edge surface 76 of the semi-cylindrical cutout has moved beyond the adjacent transverse edge surface 78 of the inlet port 28, so that the valve is entirely shut off. If the control knob 46 is now rotated in a counterclockwise direction, the combined rotational and axial movement thus imparted to the valve member 12 causes the adjacent corners of the two ports 28 and 30 to move diagonally into overlapping relation with relation to one another. The rotational or transverse movement of the valve member 12 causes the two adjacent vertical edges of the respective ports to overlap, whereas the longitudinal component of valve movement causes the cooperating transverse edges 76 and 78 to overlap to produce the rectangular opening of Fig. 8, this opening being thereafter increased by continued rotational movement of the knob 46 to the fully opened position of Fig. 7, in which the driven support may be assumed to be moving at a maximum speed of the machine.

The valve mechanism above described has the advantage that it can be adjusted to operate with a high degree of precision, particularly over the slow speed range of adjustment, while at the same time the valve parts are of simple construction and are inexpensively produced without any necessity for maintaining a high standard of precision in manufacture. A feature of the invention which contributes in large measure to the highly accurate results obtained, consists in the means for adjustment employed in connection with the setting up of the valve mechanism so that the exact point of blanking off of the throttle aperture is readily determined, and an accurate scale of speed adjustments may be obtained particularly over the slow speed range of the valve. The combination of the cooperating rectangular valve ports and the screw-threaded connection for controlling the relative movement of the valve and valve sleeve elements has been found of advantage in that it automatically provides for a slow rate of increase of valve aperture for the initial increments of relative movement from closed to open position of the valve, and thus permits the use of substantial increments of movement to produce the very fine speed changes required at the low speeds of support movement. In this connection also, the provision of the take-up spring 64 is of particular value to insure the elimination of backlash in the screw thread and the consequent maintenance of a high degree of accuracy in the critical axial setting of the valve element.

A preferred and advantageous method for effecting the adjustment of the valve mechanism is illustrated and will be described in connection with Figs. 10 to 21 inclusive of the drawings. As best shown in Figs. 10 and 11, for purposes of adjustment the hand knob 46 has been removed, a pin wrench 84 has been applied to the adjustable nut 44, and an adjusting dog 86 having a split clamping portion and clamping screw 88 is secured to the valve stem 34 in place of the manual control knob 46. The dog is provided at its outer end with a pointer 90 having a wedge-shaped tip. A short control link 92 is loosely pivoted to the stem of the pointer 90.

For convenience in setting up the valve mechanism, a transverse screw driver slot 94 is formed in the end of the valve stem exactly parallel to the face of the semi-cylindrical cutout 30 formed in the valve member 12. A punch mark 96 is formed in the end of the valve stem 34 at one side of the slot 94 and in the same relation thereto as the semi-cylindrical segment 74 left by the cutout 30 at the end of the valve member 12.

The several steps of the operation of adjusting the valve mechanism are briefly as follows: The adjusting dog 86 is mounted on the valve stem 34 with the pointer 90 in position vertically above the valve stem 34, and with the punch mark 96 also in line with the pointer 90 as shown, for example, in Figs. 10, 11 and 17. The screws 54 on the nut clamping collar 52 are backed off just enough to permit the nut 44 to be turned with the pin wrench 84. With the hydraulic pressure on the system, the control support which may be assumed to be a grinding machine work supporting table, will either move indicating that the valve member 12 is retracted out of the valve sleeve 14 so far as to uncover the inlet port 28, or the table will be stopped, showing that the semi-cylindrical segment 74 is projected sufficiently into the sleeve 14 to blank off the port 28. In either event, the nut 44 is rotated while the valve stem is held stationary in the position of Fig. 10. Assuming that the nut is provided with a right hand thread, a clockwise rotation of the nut will tend to open, and a counterclockwise movement will tend to close the inlet port 28. In this manner the exact point of blanking off is determined, and from that point the nut is rotated counterclockwise one-half to three-quarters of a turn to produce a definite overlap to blank off the inlet port 28. This is the position shown in Figs. 12 and 17 of the drawings. The second step in the operation of adjustment is, while leaving the nut stationary, to rotate the valve stem by means of the dog 86 in a counterclockwise direction until the table starts. The blanking off point thus arrived at is the position shown in Figs. 13 and 18. The blanking off point as shown in Fig. 18, is marked with a pencil on the surface of the clamping ring 52 in alignment with the pointer 90 of the dog. As a third step in the operation, the valve stem 34 is rotated counterclockwise to the position shown in Figs. 14 and 19, that is, with the dog pointer directly beneath the valve stem, the nut 44 being held stationary. For this position of the parts, the valve is wide open and the table is moved at a maximum speed governed by pump capacity. As a fourth step in the operation, while holding the valve stem stationary, the nut 44 is turned counterclockwise until the table just stops. This is the position shown in Figs. 15 and 20 of the drawings. It will be noted that Figs. 13 and 18 show one preliminary blanking off position in which the cooperating longitudinal edges of the ports 28 and 30 are about to overlap as the result of the rotational movement of the valve member 12, while Figs. 15 and 20 show another preliminary blanking off position in which the adjacent transverse edges of the ports 28 and 30 are about to move into overlapping position as the result of relative axial movement of the valve member 12 and valve sleeve 14.

From the position shown in Figs. 15 and 20, the valve stem and nut will now be rotated in unison in a clockwise direction until the pointer on the dog 86 lines up with the pencil mark on the surface of the clamping ring 52. In order to

assist in this operation, the link 92 is moved on top of the handle of the pin wrench 84 and the two parts are held together by finger pressure during the rotational movement to the position of Figs. 16 and 21. The valve mechanism is now in the position of adjustment. The clamping screws 54 are tightened to cause the clamping ring 52 to rigidly secure the nut 44 in adjusted position, and the dog 86 is removed and replaced with the dial control knob 46 which is now set so that the speeds indicated thereon check with the table speeds. The setting of the dial knob is accomplished by holding the knob against its slow speed stop while turning the valve stem, using a screw driver fitted into the screw driver slot 94 for this purpose until the desired slow speed is reached. The locking set screw 48 is now tightened, completing the operation.

It has been found that the series of operations above described are capable of securing a very accurate adjustment of the valve mechanism, for the reason that each of the blanking off positions is arrived at separately, so that in each instance the aperture resulting from the overlapping of adjacent edges of the ports 28 and 30 is the product of the very small dimension in the direction of overlapping and of a relatively large transverse dimension, so that the effective opening increases from zero very rapidly. It will be understood that the invention is not limited to the specific embodiment shown, and that various deviations may be made therefrom without departing from the spirit and scope of the appended claims.

What is claimed is:

1. A hydraulic control valve which comprises a cylindrical valve element and a cylindrically chambered valve receiving element, said valve element and chambered valve receiving element having cooperating valve ports formed with rectilinear transverse and longitudinal edges substantially square with the axis of said cylindrical elements and arranged to be brought into overlapping relation by movement of the valve element to provide a throttle opening, a nut, an extension of the valve element threaded to the nut, said valve and chambered valve receiving elements being disposed with relation to one another so that the screw movement of the valve element relative to the nut effects a substantially simultaneous overlapping of the cooperating transverse and cooperating longitudinal edges of said ports to increase the area of the throttle opening of said valve from closed to open position, and means supporting the nut in fixed axial relation to the valve receiving element and for rotatable adjustment with relation thereto, whereby rotation of the screw from a fully closed position of the valve will indicate the adjusted angular position of the threaded extension with relation to said supporting means for the blanking-off of said longitudinal edges, and a rotational adjustment of the nut relative to the threaded extension will indicate the adjusted position of the threaded extension axially with relation to the nut for the blanking-off of said transverse edges, and a subsequent rotational movement of the nut and threaded extension as a unit to the previously adjusted angular position of the threaded extension will accurately determine the shut-off position of the valve.

2. A hydraulic control valve which comprises a cylindrical valve element and a cylindrically chambered valve receiving element, said valve

9.

element and chambered valve receiving element having cooperating valve ports formed with rectilinear transverse and longitudinal edges substantially square with the axis of said cylindrical elements and arranged to be brought into overlapping relation by movement of the valve element to provide a throttle opening, a nut, an extension of the valve element threaded to the nut, said valve and chambered valve receiving elements being disposed with relation to one another so that the screw movement of the valve element relative to the nut effects a substantially simultaneous overlapping of the cooperating transverse and cooperating longitudinal edges of said ports to increase the area of the throttle opening of said valve from closed to open position, means supporting the nut in fixed axial relation to the valve receiving element and for rotational adjustment with relation to said threaded extension for adjustment of the rotational and axial position of the threaded extension to effect said simultaneous overlapping of said transverse and longitudinal edges, and spring means connected to bias the valve element axially against the nut and thereby to eliminate backlash in the threaded connection with the nut comprising a coil spring coiled about and secured to the valve extension, and a sleeve thrust element engaged by said coil spring keyed to slide upon and turn with said sleeve extension.

3. A hydraulic control valve which comprises a cylindrical valve element and a cylindrically chambered valve receiving element, said valve element and chambered valve receiving element having cooperating valve ports formed with rectilinear transverse and longitudinal edges substantially square with the axis of said cylindrical elements and arranged to be brought into overlapping relation by movement of the valve element to provide a throttle opening, a nut, an extension of the valve element threaded to the nut, said valve element being disposed with relation to the chambered valve receiving element so that a screw movement of the valve element outwardly relative to the nut effects overlapping of the cooperating transverse and cooperating longitudinal edges of said ports to increase the area of the throttle opening of said valve from closed to open position, means supporting the nut in fixed axial relation to the valve receiving element and for rotational adjustment with relation to said threaded extension for adjustment of the rotational and axial position of said threaded extension to effect said simultaneous overlapping of said transverse and longitudinal edges, a manual control disposed at the outer end of said valve extension, and spring means connected to bias said valve element axially outwardly against the nut.

4. A hydraulic control valve which comprises a cylindrical valve element and a cylindrical chambered valve receiving element, said valve element and chambered valve receiving element having cooperating valve ports formed with rectilinear transverse and longitudinal edges substantially square with the axis of said cylindrical elements and arranged to be brought into overlapping relation by movement of the valve element to provide a throttle opening, a nut, means supporting the nut in a fixed axial relation to the valve receiving element and for rotational adjustment relative thereto, an extension of the valve element threaded to the nut, said valve and chambered valve receiving elements being disposed with relation to one another so that the screw movement

10

of the valve element relative to the nut effects a substantially simultaneous overlapping of the cooperating transverse and cooperating longitudinal edges of said ports to increase the area of the throttle opening of the valve from closed to open position, fastening means for the nut arranged to permit rotational adjustment thereof for adjustment of the relative rotational and axial position of the threaded extension to effect said simultaneous overlapping of said transverse and longitudinal edges, an indicator dial arranged for rotational adjustment on said valve extension to accord with a relative angular blank-off position of said valve elements, and a relatively fixed indicator cooperating with said dial.

5. A hydraulic control valve which comprises a cylindrical valve element and a cylindrically chambered valve receiving element, said valve element and chambered valve receiving element having cooperating valve ports formed with rectilinear transverse and longitudinal edges substantially square with the axis of said cylindrical elements, a nut threaded to the valve element, means for supporting the nut in a rotatably adjustable axially fixed relation to the valve receiving element for independent adjustment of the axial and rotational position of the threaded valve element for blanking-off of said respective transverse and longitudinal edges to effect a simultaneous overlapping of said transverse and longitudinal edges at adjacent corners of said ports moving from a closed to an open position, a dial supporting manual controller secured to said valve element for adjustment angularly to accord with the rotationally adjusted blank-off position of the valve element, and a stop device acting against said manual controller to limit the rotational movement thereof.

6. A hydraulic control valve which comprises cylindrical valve and valve sleeve elements, said valve element having a semi-cylindrical cut-out formed at the inner end thereof to provide a port having rectilinear transverse and rectilinear longitudinal edges substantially square with the axis of said valve elements, said valve sleeve having formed therein a transverse slot of a length axially of the valve sleeve element less than the length of the cut-out in the valve element and of a depth extending nearly to the axis of the sleeve element to provide a side port having rectangular transverse and longitudinal edges, a nut threaded to one of said elements, a support on which the nut is fixed axially with relation to the other of said elements and for rotational adjustment with relation thereto for effecting an independent determination of the relative rotational and axial blanking-off positions of said valve elements to effect a simultaneous overlapping of said transverse and longitudinal edges for a throttled opening of the valve, and means for securing the nut to the support in an adjusted position.

7. A hydraulic control valve which comprises a cylindrical valve element and a cylindrically chambered valve receiving element, said valve element and chambered valve receiving element having cooperating valve ports formed with rectilinear transverse and longitudinal edges substantially square with the axis of said valve elements and arranged to have adjacent corners thereof brought into overlapping relation by movement of the valve element to provide a throttle, a nut having a threaded connection with one of said cylindrical valve elements, a support on which the nut is fixed axially with relation to the other

of said cylindrical valve elements and for rotational adjustment with relation thereto for effecting an independent determination of the relative rotational and axial blank-off positions of said valve elements, means on said support marking the angular blank-off position of the movable cylindrical valve element, means securing the nut to said support for a position in which the movable sleeve element is in said marked rotational position and in which the nut and movable cylindrical valve element are in said determined axial blank-off position, and a dial supporting manual controller rotatably adjustable on said movable valve element to accord with the adjusted positions of said nut and threaded sleeve valve element.

8. A hydraulic control valve which comprises cylindrical valve and valve sleeve elements, said valve element having a semi-cylindrical cut-out formed at the inner end thereof to provide a port having rectilinear transverse and rectilinear longitudinal edges substantially square with the axis of said valve elements, said valve sleeve having formed therein a transverse slot of a length axially of the valve sleeve element less than the length of the cut-out in the valve element and of a depth extending nearly to the axis of the sleeve element to provide a side port having rectilinear transverse and longitudinal edges, a nut, a

threaded extension of said valve element threaded to the nut, said valve and sleeve elements being disposed with relation to one another so that a screw movement of the valve element outwardly relative to the nut effects a substantially simultaneous overlapping at adjacent corners of the cooperating transverse and longitudinal edges of said ports to open the valve, means including a ring clamp supporting the nut in fixed axial relation to the valve receiving element and for rotational adjustment with relation thereto to determine the relative angular and relative axial blank-off positions of said valve elements, and a dial supporting manual controller angularly adjustable on said valve extension in accordance with the angularly adjusted blank-off position of said valve extension.
